UNITED STATES PATENT OFFICE.

JAMES M. GILBERT, OF PUTNEY, VERMONT, ASSIGNOR OF ONE-HALF TO
GEORGE M. GILBERT, OF SIOUX CITY, IOWA.

TRANSPOSING KEY-BOARD.

SPECIFICATION forming part of Letters Patent No. 447,641, dated March 3, 1891.

Application filed October 15, 1890. Serial No. 368,164. (No model.)

To all whom it may concern:

Be it known that I, JAMES M. GILBERT, of Putney, in the county of Windham and State of Vermont, have invented a new and Improved Transposing Key-Board, of which the following is a full, clear, and exact description.

My invention relates to improvements in transposing key-boards for musical instruments; and the object of my invention is to produce a transposing key-board which may be quickly and easily adjusted, so that while music is being played as written it will in reality be produced in a higher or lower key, as the case may be.

To this end my invention consists in certain features of construction and combinations of parts, which will be hereinafter fully described, and then pointed out in the claims.

Reference is to be had to the accompanying drawings, forming a part of this specification, in which similar letters of reference indicate corresponding parts in all the figures.

Figure 1 is a broken perspective view, partly in section, of the ordinary keys of a piano and the transposing key-board mounted above the keys. Fig. 2 is a transverse section on the line 2 2 of Fig. 1. Fig. 3 is a detail sectional plan of the hand-wheel for adjusting the key-board and the spring-catch for locking the hand-wheel, the view being taken on the line 3 3 of Fig. 2. Fig. 4 is a broken plan showing the key-board frame in position in the piano-case, but with the finger-keys removed. Fig. 5 is a broken sectional view on the line 5 5 of Fig. 2. Fig. 6 is a broken sectional view showing the application of the transposing key-board to an organ, and Fig. 7 is a plan of the same with the finger-keys removed.

The piano-case A is of the usual construction, having at each end of the key-board the horizontal boards a, which are arranged so that the key-board may slide beneath them, and the case has the usual horizontal partition B, to a cross-bar B' of which are pivoted the keys C, which are of the usual construction, except that they are not provided with finger-keys. The keys C are guided by pins c, which extend upward from a cross-bar C'

in the usual manner, so as to enter slots in the front ends of the keys, and the front ends of the keys have thin pieces of felt or other suitable material upon their upper sides to prevent noise when the upper keys strike 55 upon them.

The keys of the transposing key-board are mounted in a rectangular frame which slides in the piano-case, and which consists of the parallel front and rear rails D and the connecting end rails D', the end rails D' being widened at their front ends, as shown at d in Figs. 2 and 5, so that the rear rail D is higher than the front rail of the frame, and consequently extends above the rear ends of the 65 keys in the transposing key-board.

A cross-bar E extends through the piano-case behind the rear rail D of the key-board frame, and on the upper and lower sides of the cross-bar are forwardly-extending clips 70 E', which are bent over at their forward ends, as shown at e, so as to fit upon corresponding shoulders of the rear rail D, and thus guide the key-board frame.

Located in the case at each side of the main 75 keys C are short strips F, which serve as guides and prevent the upper keys or the keys of the key-board from dropping down when they are moved from above the lower keys. The upper keys G, which form the finger-keys 80 of the transposing key-board, are pivoted to the rear rail D of the rectangular frame by means of the blocks H, there being a block for each key, and the blocks are attached firmly to the rear rail D of the key-board 85 frame and have depending tongues h at their lower ends, which project into slots in the keys G and to which the keys are pivoted by suitable pins. On the rear ends of the keys G and on the upper sides are weights J, which 90 are screwed to the keys, and by properly adjusting the weights the keys may be nicely balanced.

The front rail D of the key-board frame lies flatwise upon the partition B, and extending along the upper surface of the rail and on opposite sides thereof are the parallel bars K and K', the front bar K having upon its upper edge guide-pins k, which extend into slots in the longer or natural keys G, and 100

the rear bar K', having similar pins extending into corresponding slots in the shorter keys of the key-board, and while I have shown the bars K and K' as separate from the front rail D, it is obvious that the rail and bars may, if desired, be made in one piece.

A transverse bar L extends between the parallel bars K and K', the bar being pivoted to the front bar K by means of the links L', which are located near the ends of the bar L, and it will thus be seen that the bar may be moved vertically, but cannot be displaced. The bar L rests normally upon the stop-blocks L².

15 As shown in Fig. 1, the front rail D of the key-board frame is slotted longitudinally, the slot aligning with the transverse bar L, and fixed in one side of the slot is a rack M, which meshes with a pinion N, the pinion being fixed 20 to a shaft N', which extends downwardly through the partition B, which forms the bottom of that part of the case which is immediately beneath the key-board. The shaft N' turns in a suitable sleeve n, and fixed to the 25 lower end of the shaft is a hand-wheel N², which has perforations n' extending vertically through it and arranged at regular intervals therein.

30 A flat spring O is fixed to the under side of the partition B at one end, and the free end of the spring presses upon the upper side of the hand-wheel N², and is provided with a depending stud o, which enters one of the perforations n' of the hand-wheel and thus 35 prevents the wheel from being turned, and if the hand-wheel is locked it will be seen that on account of its connection with the key-board frame the key-board will be also locked, so that it cannot be accidentally moved. A pin 40 P extends vertically through the partition B and through a suitable guide-block P' on the upper side of the partition, the upper end of the pin impinging on the lower side of the transverse bar L and the lower end of the pin 45 impinging upon the upper side of the spring O. It will thus be seen that when the spring O is raised to unlock the hand-wheel the pin will also raise the transverse bar L, and that pressing against the lower sides of the keys 50 G will raise these keys from contact with the keys C, so that the key-board frame may be moved to the right or left, as desired.

To shift the key-board the operator raises the spring O, thus unlocking the hand-wheel and 55 raising the keys, as shown, and the hand-wheel is then turned to the right or left, as desired, thus causing the pinion N to actuate the rack M and the key-board frame, and upon releasing the spring the stud o immediately enters 60 one of the perforations of the hand-wheel and locks the hand-wheel and the key-board, as above described.

In Figs. 6 and 7 I have shown the key-board as applied to an organ, and in these 65 figures the device is substantially the same, but only one set of keys is necessary. The organ-case A' has the usual horizontal parti-

tion B², and on the upper side of the partition near the ends are cross-bars Q, upon which is mounted a rectangular frame D^a, 70 the frame being adapted to slide thereon, and upon the front and rear sides of the frame are produced flanges d', which are overlapped by the angular clips q, attached to the front and rear ends of the cross-bars Q, and the 75 clips thus serve as guides for the frame. The frame D^a has keys G^a pivoted therein, the keys being of the usual construction, except that they are slotted horizontally on their rear ends, as shown at g, and the keys are 80 pivoted to the frame at their rear ends by means of the pins g'. An angular clip R is fixed to the rear rail of the frame D^a and enters the slots in the rear ends of the keys, thus serving as a guide and preventing the 85 displacement of the keys.

Beneath the frame D^a is a transverse bar S, and pins S' extend vertically through the bar in alignment with the keys G^a, the upper ends of the pins impinging on the lower edges 90 of the keys, and the lower ends of the pins impinging upon the levers T, which operate the reed mechanism of the organ in the usual manner. The frame is also provided with a transverse bar L for raising the keys in the 95 manner already described, with suitable guide-pins k, which enter slots in the keys, and with the rack-and-pinion movement already described for moving the frame. The organ-case has rods t fixed to the inner sides at each 100 end, so as to project over the frame D^a, and the rods serve to prevent the keys from falling down when they are moved to one side of the reed-levers T.

It will be seen that when the keys G of the 105 piano or the keys G^a of the organ are moved to one side they will be moved also beyond the piano-keys C or the organ-levers T, and in order that the instruments may always be played up to their full capacity they are provided with extra finger-keys, there being enough extra keys so that the piano-keys C and the organ-levers T will all be constantly covered. The instruments are played in the usual manner, and when the keys G of the 115 piano are depressed they operate upon the keys C, causing them to operate the piano-hammers in the usual manner, and when the organ-keys G' are depressed they cause the pins S to operate upon the levers T, so that 120 any one who can play an instrument of the ordinary construction can play upon it when provided with the transposing key-board.

To facilitate the adjustment of the transposing key-board, that part of the case of the 125 piano or organ which is immediately behind the finger-keys is lettered, as shown in Fig. 1, the letters corresponding to the permanent keys of the instrument and being directly above the same, and the C keys of the transposing key-board are marked preferably with an arrow, and when the arrows are opposite the letters C on the case the instrument will be in its normal position, or at concert pitch,

and the change made by shifting the key-board will be indicated by the position of the arrows in relation to the letters on the case.

Having thus described my invention, I claim as new and desire to secure by Letters Patent—

1. A transposing key-board comprising a movable frame having the finger-keys pivoted therein, a rack-and-pinion movement for actuating the frame, and a locking device for the pinion, substantially as described.

2. A transposing key-board comprising a movable frame, a series of finger-keys pivoted in the frame, said keys having guide-pins, as shown, a vertically-movable bar extending transversely beneath the keys, means for raising the bar, a rack-and-pinion movement for operating the frame, and a locking device for the pinion, substantially as described.

3. A transposing key-board comprising a laterally-movable frame having a series of keys pivoted therein, said keys having suitable guide-pins, as shown, a guide for the frame, a rack-and-pinion movement for operating the frame, and a locking device for the pinion, substantially as described.

4. The combination, with the keys of a transposing key-board and the frame in which they are pivoted, of a bar pivoted transversely below the keys, a rack on the frame, a pinion engaging the rack, and a lock for the pinion, which lock is also in engagement with the pivoted bar, substantially as described.

5. A transposing key-board comprising a frame, a series of keys pivoted in the frame and provided with suitable guide-pins, a transverse bar extending beneath the front ends of the keys, a rack-and-pinion movement for operating the frame, a pinion-shaft having a perforated handle located beneath the case of the instrument, a spring having one end fixed to the instrument beneath the key-board and having its free end provided with a stud adapted to enter the perforations of the pinion - handle, and a pin extending through the instrument-case, having its upper end impinging on the transverse bar and its lower end on the spring, substantially as described.

6. The combination, with a piano, of a frame

mounted above the piano-keys and having a series of finger-keys pivoted therein, suitable guides for the frame and for the keys, a vertically-movable bar extending transversely beneath the keys, said bar having a link connection with the frame, as shown, a rack-and-pinion movement for operating the frame, a pinion-shaft having a perforated handle located beneath the case of the instrument, a spring having one end fixed to the instrument-case and the free end provided with a stud to enter the perforations of the pinion-handle, and a pin extending vertically through the case, its upper end impinging on the transverse bar and its lower end impinging on the spring, substantially as described.

7. In a transposing key-board, the combination of the movable frame, the blocks fixed to the rear rail of the frame and provided with depending tongues, and the finger-keys having slots therein to receive the tongues, substantially as described.

8. In a transposing key-board, the combination of the movable frame, the blocks fixed to the rear rail of the frame and provided with depending tongues, and the finger-keys having slots to receive the tongues, said keys being pivoted to the tongues and having their rear ends provided with weights, substantially as described.

9. In a transposing key-board, the combination, with the movable frame having the finger-keys pivoted therein, of a cross-bar extending above the keys, and clips fixed to the cross-bar and having their ends bent to embrace and guide the end rail of the frame, substantially as described.

10. In a transposing key-board, the combination of the movable frame, the rack-and-pinion movement for operating the frame, the perforated handle of the pinion-shaft, and the spring fixed to the instrument-case and provided at its free end with a stud adapted to enter the perforations of the pinion-handle, substantially as described.
